UNITED STATES PATENT OFFICE

WILLIAM F. LAHEY AND MAURICE S. LAHEY, OF NEW CANAAN, CONNECTICUT

STORM WINDOW CONSTRUCTION

Application filed May 31, 1930. Serial No. 458,189.

This invention relates to improvements in window construction and has for an object to provide an improved window and frame construction which may be mounted the same as the standard frame and which will have means permitting entrance of outside air to the room for ventilation, with means for controlling entrance of air, together with an improved storm window construction so arranged that ventilation may be secured when the storm window is or is not in position.

It is another object of the invention to provide an improved storm window construction to be used with standard or other frames which is of an improved construction and may be raised with a simple operation for opening the window, and may also be swung outwardly to a downwardly inclined position to take the place of an awning to prevent entrance of rain, or it may be covered with an opaque material to exclude sunlight and give an awning or canopy effect.

With the foregoing and other objects in view, we have devised an improved window construction, one form of which is illustrated in the accompanying drawings forming a part of this specification.

In these drawings

Fig. 1 is a vertical section through our improved window construction taken substantially on line 1—1 of Fig. 2.

Fig. 2 is a front elevation on a somewhat reduced scale looking toward the outside of the window.

Fig. 3 is a view similar to Fig. 1 showing the storm window in open position.

Fig. 4 is a detailed section substantially on line 4—4 of Fig. 1.

Fig. 5 is a detailed section of a means for controlling the ventilation.

Fig. 6 is an elevation of the lower glass of the storm window.

Fig. 7 is a detailed section substantially on line 7—7 of Fig. 1, and

Fig. 8 is a detail of a catch which may be used to hold the lower glass in raised position.

The window construction comprises the standard frame construction including the upright side finishing members 10 and top member 11 on the outside, together with the

finishing member 12 on the inside, with the usual runways for the upper and lower sash 13 and 14, respectively. Any suitable type of runways may be used for the sash, those shown including upright metal strips 15 secured to the sides of the frame and which project into grooves in the edges of the sash to guide them for vertical sliding movement, but any suitable type of runway may be employed. A similar bar 16 is shown across the top of the upper sash to make a weather tight connection. The window frame construction also includes the usual outwardly and downwardly inclined sill member 17.

Ordinarily, the frame is open at the top, but we close this top by member 18 forming a chamber 19 in the upper part of the frame. In the lower wall member 20 of this chamber we provide an outlet passage 21 from the chamber 19 to the room at the inside 70 of the sash and provide another passage 22 leading to this chamber 19 from outside the sash to permit entrance of fresh air to the room through the upper part of the window frame for ventilating purposes. The passage 22 is preferably surrounded by a guard 23 to prevent rain or snow blowing into the chamber. Any desirable means may be employed for controlling the entrance of this air. A very simple and effective means comprises a damper 24 over the passage or opening 21. An angular support 24 may be secured to one end of this damper to rest on the top of the member 20 and a spring member 25 secured to the other end of the damper 24 to engage the other edge 26 of the opening and frictionally hold the damper in any desired position. The free end 27 of the spring may be bent laterally to rest on the top of the member 20 to limit opening movement 90 of the damper and any desired handle 28 may be employed for manipulating the damper.

The improved storm window construction is mounted in the window frame outside the sash. It comprises a frame having upright side members 29, a top member 30 and a transverse lower bar 31. It is hinged in the frame at its upper end by hinges 32 secured to the member 11 and the top bar 30. This

bar 30 is provided also with a longitudinal recess 33 in alignment with the inlet passage 22 to permit entrance of air for ventilation when the storm window is in position.

- 5 The side members 29 are provided with guide grooves 34 to receive the edges of the upper glass 35 and the lower glass 36, these grooves being of sufficient width to receive both panes of glass in superposed relation as shown in Fig. 3. The full width of the groove, however, does not extend through the lower end of the frame, but at the lower end is only of sufficient width for passage of one glass, thus providing shoulders 37 at the lower end of these grooves to retain the upper glass 35 in position. The bar 31 may carry a rubber, felt or other packing 38 which is somewhat yieldable and resilient to prevent rattling of the glass and to make a tight joint at this point.

10 The lower section of the storm window comprises the lower pane of glass 36 which is not in any frame, its lower edge only being mounted in a cross bar 39, it being secured therein by any suitable means such as cross pins 40, and on its lower edge carries a rubber packing strip 41 to make a weather tight joint at the lower edge. As shown in Fig. 1, the upper edge of this lower glass extends into the side grooves 34 of the hinged frame members 29 between the lower edge of the upper glass 35 and the packing 38 and bar 31. It thus, retains the upper glass 35 over the shoulder 37 so that this upper glass can not slide out of the frame. Although the lower glass 36 is not mounted in any movable frame, its side edges are guided for vertical sliding movement in the grooves 42 provided in stationary members 43 mounted on the inner surface of the sides 44 of the window frame. These members 43 extend upwardly for a sufficient distance to support the edges of the glass 36 when this glass is in its lower position, but when the glass 36 is raised, as shown in Fig. 3, the glass passes out of the grooves 42 so that the hinged frame and both sheets of glass can be swung outwardly on the hinges 32 as indicated in Fig. 3.

- 15 Thus, when it is desired to open the storm window, the lower glass 36 may be raised by sliding it upwardly in the grooves 42 and into the grooves 34 in the side members 29 of the hinged frame. This is the position shown in Fig. 3 and it may be held in this position by a suitable catch 45 carried on the lower bar 31 or the bar 39 to detachably engage a suitable holding member on the other bar. When raised in this position as indicated above, the glass 36 is out of the grooves 42 and the whole hinged frame may be swung outwardly to the position of Fig. 3. It may be held in this position by any suitable means such as one or more hinged braces 46 detachably engaging a stud 47. This holds the storm window construction in a downwardly

and outwardly inclined position giving a canopy or awning effect to prevent rain blowing into the window, and may also provide a shelter when used for wayside refreshment stands and the like. This storm window construction is especially adapted for use with any type of window. It may be used for storm sash for porches as well as house windows, and is adapted for use in sanitariums, sleeping porches, hospitals, refreshment stands and the like. It is easily applied and removed, although it is not necessary to remove it in order to open the window for free circulation of air. It is set in from the outer edge 48 of the frame so that the window blinds may close into the frame in the usual manner.

20 It will be evident that in closing this storm window, the braces 46 are first released and the upper frame then swung inwardly to the upright position. This movement is limited by the runway bar 49. This brings the edges of the lower glass 36 into alignment with the guide grooves 42 and the lower glass 36 may then be slid downwardly therein to the position of Fig. 1 in which position the storm window covers the entire window opening. If the lower member 39 is locked, the window is completely locked.

25 If it is desired to remove the glasses 35 and 36, all that is necessary is to raise the glass 36 into the hinged frame members 29, then swing the lower end of this frame outwardly to clear the guide members 43. Lower glass 36 may now be drawn downwardly 100 out of the hinged frame as indicated in dotted lines, Fig. 3. After the glass 36 is removed, glass 35 drops to the lower side of the grooves 34 away from the shoulders 37 and may be slid out of the frame through the space normally occupied by the glass 36. This permits of easy renewal of either pane of glass.

30 If desired, a shading effect may be secured by placing an opaque sheet of material 50 on the underside of the glass 36 when in its raised position and securing it in this position by any suitable means such as a spring clamp 51 seated at its opposite ends in recesses in the frame. This will be a still further awning or canopy effect. Or instead of the glass we may use sheets of metal. This will give an opaque construction to close up the entire window as when closing the house for the summer, and these metal plates would be very effective in preventing easy access to the building through the window. This will be evident from the fact that when the window is closed the lower member 36 is in the grooves 42 and the upper member 35

35 in the frame 29. Thus, if the members 35 and 36 are of metal the window will be difficult to gain access through if it is locked from the inside. For wayside stands it may be very desirable that members 35 and 36 be of metal. They would then not only pro-

vide an effective canopy when the frame is swung out as in Fig. 3, but when closed as above described, the window is effectively sealed for the night or for the winter and is 5 very difficult to gain access through. It is to be understood that where the term "glass" is used in the claims for members 35 and 36, it is used in the generic sense for a plate to close the opening and may include plates of 10 glass, metal, wood or other suitable material.

Having thus set forth the nature of our invention, what we claim is:

1. In a window construction, a frame having runways for sash, a storm window construction mounted in the frame outside said sash comprising a frame hinged to the window frame at the top and having grooves in the edges of its opening to hold a glass, the side grooves opening through the bottom member of the hinged frame to provide guides for a second glass below the first glass, and guides in the window frame for the upright side edges of the lower glass. 20

2. In a window construction, a frame having runways for sash, a storm window construction mounted in the frame outside said sash comprising a frame hinged to the window frame at the top, said hinged frame having grooves in its side members opening through the lower end of the frame for insertion of a glass, a second glass in said slot and adapted to slide in said grooves, and guides for the upright edges of the second glass at the opposite side of the window frame and in 30 alignment with said grooves when the hinged frame is in its lower position.

3. In a window construction, a frame having runways for sash, a storm window construction mounted in the frame outside said sash comprising a frame hinged to the window frame at the top and adapted to cover only approximately the upper half of the window opening, a glass in said hinged frame, a lower glass guided for vertical sliding movement in the hinged frame and adapted to be extended below the same, and upright guideways for said lower glass at the opposite sides of the window frame. 45

4. In a window construction, a frame having runways for sash, a storm window construction mounted in the frame outside said sash comprising a frame hinged to the window frame at the top, the sides of said frame having grooves to receive the side edges of 55 the glass and opening through the lower end of the frame, said grooves being of sufficient width to receive two sheets of glass except at their lower ends at which they are of a width for a single pane of glass, a lower glass in said lower ends of the grooves and adapted to be slid into said grooves at one side of the first glass, means for holding the frame downwardly and outwardly inclined, and upright guides for the edges of the lower glass at the 60 opposite sides of the window frame.

5. In a window construction, a frame having runways for sash, a storm window construction mounted in the frame outside said sash, comprising a frame hinged to the window frame at the top, said hinged frame being 70 adapted to cover approximately the upper half of the window opening and having means to hold two panes of glass in superimposed relation, a guide in the lower part of the hinged frame in which the lower glass is 75 slidable and from which it may be extended to cover the lower part of the window opening, and upright guides at the opposite sides of the window frame to receive the edges of the lower glass when it is in its lower position. 80

6. A window construction comprising a frame hinged at its upper end and adapted to cover the upper portion of a window opening, a glass in said frame, a lower glass mounted to slide in said frame to one side of the first glass, and stationary guides for the lateral side edges of the lower glass in alignment with the guides in the frame when the frame is in closed position. 85

7. A window construction comprising a frame adapted to cover the upper portion of a window opening, the side members of said frame having guide grooves for the edges of a glass opening through the lower end of the frame, a lower glass guided for sliding movement in said grooves and adapted to project from the lower end of the frame, and stationary guides for the opposite side edges of the lower glass when so extended and in alignment with those in the frame when the frame 95 is in closed position. 100
